(57) CLAIM

The ornamental design for a bottle with handle, as shown and described.

DESCRIPTION

FIG. 1 is a side elevational view of a bottle with handle showing our new design, the opposite side elevational view being a mirror image thereof;

FIG. 2 is a rear elevational view thereof;

FIG. 3 is a top plan view thereof;

FIG. 4 is a top perspective view thereof; and,

FIG. 5 is a bottom perspective view thereof.
